(57) **CLAIM**

The ornamental design for a firearm mount with sighting module, as shown and described.

DESCRIPTION

FIG. 1 is a rear perspective view of a firearm mount with sighting module showing my new design.

FIG. 2 is a front view of the firearm mount with sighting module.

FIG. 3 is a rear view of the firearm mount with sighting module.

FIG. 4 is a left view of the firearm mount with sighting module.

FIG. 5 is a right view of the firearm mount with sighting module.

FIG. 6 is a top view of the firearm mount with sighting module; and,

FIG. 7 is a bottom view of the firearm mount with sighting module.

The broken line portion of the figure drawings is included to show unclaimed subject matter only and forms no part of the claimed design.
